BREAKER STRIP AND CONTROL ASSEMBLY

Florence B. Anderson, Winnetka, Ill., assignor to Motor Products Corporation, Detroit, Mich., a corporation of New York

Application November 17, 1952, Serial No. 320,834

6 Claims. (Cl. 62—89)

This invention relates generally to the art of refrigeration and refers more particularly to a refrigerator cabinet including a sub-assembly embodying a breaker strip having temperature regulating and/or defrost timer control units attached thereto.

It is an object of this invention to provide an attractive breaker strip and control assembly wherein the parts thereof are constructed and arranged to form a bench assembly capable of being readily installed on a refrigerator cabinet.

The foregoing as well as other objects will be made more apparent as this description proceeds especially when considered in connection with the accompanying drawings, wherein:

Figure 1 is a front elevation of a refrigerator embodying the present invention and having the door for the access opening removed;

Figure 2 is a front elevational view of the combined breaker strip and control assembly embodied in the refrigerator cabinet shown in Figure 1;

Figure 3 is an enlarged cross sectional view taken substantially on the plane indicated by the line 3—3 of Figure 1;

Figure 4 is a fragmentary front elevational view of the breaker strip and control assembly and having certain parts removed for the sake of clearness;

Figure 5 is an exploded perspective view of the combined breaker strip and control assembly;

Figure 6 is a cross sectional view taken on the line 6—6 of Figure 1;

Figure 7 is a front elevational view of a modified form of escutcheon plate; and

Figure 8 is a rear elevational view of the construction shown in Figure 7.

In Figure 1 of the drawings the numeral 10 designates a refrigerator cabinet having an access opening 11 at the front and having a door (not shown) for closing the opening 11. In accordance with conventional practice, the refrigerator cabinet 10 comprises an outer shell 12, a liner 13, and a breaker strip 14 surrounding the access opening 11 at the front side of the cabinet 10. The outer shell 12 has top, side and bottom walls fashioned at the front edges with laterally inwardly extending flanges 15. The liner 13 also has top, bottom and side walls spaced laterally inwardly from the corresponding walls of the shell 12 to provide a space for accommodating suitable thermal insulation, not shown herein. The front edge portions of the liner walls are fashioned to provide flanges 16 which extend laterally outwardly toward the flanges 15 on the shell 12 and terminate short of the flanges 15.

The breaker strip 14 is formed of a heat insulating material and is of a nature to bridge the space between the flanges 15 on the shell 12 and the flanges 16 on the liner 13. As shown in Figure 3 of the drawings, the outer edge of the breaker strip 14 is fashioned with a forked part 17 that straddles the inner edge of the flange 15 and the inner edge of the breaker strip 14 is formed with spaced hook-shaped lugs 18. As shown in Figure 6 of the drawings the lugs 18 project through openings 19 formed in the flange 16 and are engageable with the marginal edges of the openings 19.

In the present instance the breaker strip 14 comprises a top section 21, side sections 22 and a bottom section 23. The extremities of the sections aforesaid are secured to-

2

gether to form in effect a continuous breaker strip around the access opening 11 in the front of the cabinet 10.

This invention is concerned primarily with the construction of the top breaker strip 21 and it will be noted from Figure 2 of the drawings that this section has an inverted U-shaped configuration. The arrangement is such that the breaker strip section 21 extends across the top and part way down each side of the access opening 11 in the front of the cabinet 10. Located centrally of the breaker strip section 21 is a relatively large opening 24 having a rearwardly extending marginal flange 25 and having integral projections 26 extending rearwardly from the marginal flange 25 in spaced relation to each other. The purpose of the projections 26 is to removably secure a sheet metal mounting plate 27 to the breaker strip section 21 at the rear side of the latter and this mounting plate is of sufficient length to extend completely across the opening 24 through the breaker strip section 21.

As shown in Figure 5 of the drawings the mounting plate 27 has openings 28 therethrough for respectively receiving the projections 26 on the breaker strip section 21. The rear ends of the projections 26 extend beyond the mounting plate 27 and spring metal stud clips 29 are respectively secured to the rear extremities of the projections 26 to securely clamp the mounting plate 27 to the rear side of the breaker strip section 21. In the present instance, a pair of control units 30 and 31 are secured to the mounting plate 27 at the rear side of the latter. For the purpose of illustration the control unit 30 may be considered a temperature control and the unit 31 may be considered a defrost timer assembly. The units 30 and 31 may be of any suitable type capable of performing their respective operations and therefore need not be described in detail herein. Briefly, the unit 30 has an operating shaft 32 which extends in a forward direction therefrom through an opening 33 in the mounting plate 27. Also the unit 30 has attaching brackets 34 respectively positioned at opposite sides of the shaft 32 and clamped against the rear face of the mounting plate 27 by screws 35. The screws 35 extend rearwardly through clearance openings 36 in the mounting plate and are fastened to the brackets 34 by sheet metal speed nuts 37.

The control unit 31 is positioned to one side of the control unit 30 and has an operating shaft 38 which projects forwardly through an opening 39 formed in the mounting plate 27. A pair of brackets 40 are respectively secured to the control unit 31 at opposite sides of the shaft 38 and are clamped against the rear face of the mounting plate 27 by screws 41. The screws 41 extend rearwardly through openings 42 in the mounting plate 27 and are threaded into openings 43 in the brackets 40.

The mounting plate 27 is concealed from view through the opening 24 by an escutcheon plate 44 which is preferably, although not necessarily, formed of moldable plastic material and is ribbed or otherwise decorated to provide a pleasing appearance. The escutcheon plate 44 overlies the front side of the breaker strip 21 in a position to completely conceal the opening 24 and is embossed in a rearward direction at longitudinally spaced points to provide circular recesses 45 and 46 in the front face of the escutcheon plate 44. The embossed portions of the escutcheon plate 44 project rearwardly through the opening 24 in the breaker strip section 21 and the circular recesses 45, 46 are respectively coaxially arranged with respect to the operating shafts 32 and 38 of the control units. The central portions of the bottom walls 47 of the recesses 45 and 46 are embossed in a forward direction to form spherically shaped surfaces 48. As shown in Figure 4 of the drawings, the embossed surfaces 48 and the annular part of the wall 47 surrounding the surfaces 48 have indicia applied thereto for the purpose of indicating the settings of the respective control units 30 and 31.

The escutcheon plate 44 is secured to the mounting plate 27 and for accomplishing this result lugs 49 are formed on the rearwardly embossed portions of the escutcheon plate. The lugs 49 project rearwardly through the opening 24 in the breaker strip section 21 and through openings 50 formed in the mounting plate 27. As shown in Figure 5 of the drawings tubular spring clips 51 are respectively secured within the openings 50 and frictionally engage the lugs 49 to removably secure the escutcheon plate 44 in position on the breaker strip section 21.

The control units 30 and 31 are respectively operated from a position at the front side of the escutcheon plate 44 by a pair of control knobs 52 and 53 respectively. Each control knob has a shank 54 and a circular head 55. The shank portions 54 respectively extend through central openings 56 formed in the walls 47 of the recesses 45 and 46. The circular head portions 55 respectively occupy positions within the recesses 45, 46 and are spherically shaped to conform to the spherical surfaces 48 on the escutcheon plate 44. The arrangement is such that the front surfaces of the head portions 55 form in effect a continuation of the front face of the escutcheon plate 44 and thereby improve the appearance of the assembly. As shown in Figure 2 of the drawings, suitable ribs 57 extend diametrically across the heads 55 at the front side thereof to facilitate manipulation of the knobs, and windows 58 are provided in the head portions 55 to expose the indicia applied to the surfaces 47 and 48 of the escutcheon plate 44. In this connection, it is pointed out that the shank portions 54 of the control knobs are formed of metal and the head portions 55 are formed of plastic to match the plastic from which the escutcheon plate 44 is formed.

The shank portions 54 of the control knobs are of sufficient length to project rearwardly through the openings 33 and 39 in the mounting plate 27. As shown in Figure 3 of the drawings the shank portions 54 are axially bored to respectively receive the shafts 32 and 38 of the control units 30 and 31. Suitable spring rings 59 are provided on the shafts 32 and 38 for frictionally engaging the respective shank portions 54 of the control knobs to hold the latter in driving engagement with the shafts.

In certain types of refrigerators the defrost timer unit 31 is omitted and in such cases it is desirable to shift the temperature control unit 30 to a central position relative to the breaker strip section 21. Hence the mounting plate 27 has an opening 60 located midway between the openings 33 and 39 for receiving the operating shaft 32 of the control unit 30. Also the escutcheon plate 44 is replaced by an escutcheon plate 61 (Figures 7 and 8) having a central embossed portion for accommodating a control knob 62. The embossed portion of the plate 61 has circumferentially spaced projections 63 which extend rearwardly through openings 64 in the mounting plate 27 and are secured to the latter in the same manner as the projections 49 on the escutcheon plate 44.

Regardless of whether the breaker strip and control assembly has one or more control units it forms what is commonly known to the trade as a bench assembly. In other words, the breaker strip section 21, mounting plate 27, associated control unit or units, escutcheon plate 44 or 61, and associated control knobs or knob may be installed on the refrigerator cabinet as an assembly. Also, if desired, the escutcheon plate and associated control knob or knobs may be assembled subsequent to installation of the breaker strip section 21 on the cabinet. In any case the mounting plate 27 and associated control or controls thereon assume positions between the top walls of the shell 12 and liner 13 when installed, where they are concealed from view. Moreover, no part of the mounting plate 27 or of the control unit or units thereon are directly attached to the shell 12 or liner 13. Hence the breaker strip and control assembly may be quickly installed on and removed from the refrigerator cabinet.

What I claim as my invention is:

1. In a refrigerator, a cabinet having inner and outer walls spaced laterally from one another, a breaker strip extending between said walls and removably attachable to the latter, a mounting plate positioned between said walls at the rear side of the breaker strip and secured to the breaker strip, a control unit positioned at the rear side of the mounting plate and secured to said plate; an escutcheon plate clamped to the front side of the breaker strip and having a circular recess at the front side thereof, an operating knob positioned within the recess and having a shank projecting rearwardly through openings in the escutcheon plate, breaker strip and mounting plate, indicia on the front side of the base of the recess forming a dial, and a window in the operating knob through which the indicia is visible, and means removably securing the shank to the control unit for operating the latter; said breaker strip, mounting plate, control unit, and escutcheon plate forming an assembly attachable to and removable from the cabinet walls as a unit.

2. In a refrigerator having an outer shell, an inner shell, and a heat insulating breaker strip having an enlarged opening therethrough and removably mounted in spanning relationship between spaced edge portions of the shell and liner, the improvement which comprises rearwardly extending projections on said breaker strip, a mounting plate in rear of said breaker strip having openings through which said projections extend, fastening means engaged with said projections and retaining said breaker strip and mounting plate as a sub-assembly, a control device secured to the rear of said mounting plate including an operating shaft extending forwardly therefrom, an escutcheon plate larger than the enlarged opening in said breaker strip and having rearwardly extending lugs, said mounting plate having openings receiving said lugs, means retaining said lugs in said openings to mount said escutcheon plate directly to said mounting plate with the peripheral portions overlying the edge portions of the breaker strip surrounding the enlarged opening therethrough, said escutcheon plate and mounting plate having aligned openings in alignment with the shaft of said control device, an operating knob at the front of said escutcheon plate, and means extending through said aligned openings and connecting said knob to said operating shaft.

3. The structure as defined in claim 2 in which the escutcheon plate is recessed surrounding the opening therein, and said knob is seated in the recess.

4. The structure as defined in claim 2 in which the escutcheon plate is recessed surrounding the opening therein, the bottom of the recess is forwardly convex and said knob is seated in the recess and is dished to fit the forward convexity of the bottom of the recess.

5. The structure as defined in claim 2 in which the means connecting said knob and shaft comprises a hollow shank connected to said knob and extending rearwardly and frictionally gripping said shaft.

6. The structure as defined in claim 2 in which said mounting plate is provided with a plurality of openings for registration with a plurality of operating shafts of control devices mounted thereon, the enlarged opening in said breaker strip is of a size to overlie all of said plurality of openings in said mounting plate and the escutcheon plate is provided with only the required number of openings to register with the operating shafts of the control devices on said mounting plate.
